UNITED STATES PATENT OFFICE.

JOHN A. KIESELE, OF NEWARK, NEW JERSEY.

DESIGN FOR A BOX.

SPECIFICATION forming part of Design No. 34,373, dated April 16, 1901.

Application filed March 21, 1901. Serial No. 52,239. Term of patent 7 years.

To all whom it may concern:

Be it known that I, JOHN A. KIESELE, a citizen of the United States, residing at Newark, Essex county, State of New Jersey, have invented and produced a new and original Design for a Box, of which the following is a specification.

The leading feature of my design is a box, substantially as shown in the accompanying drawings, in which—

Figure 1 is a plan view of a box embodying my design, and Fig. 2 is a transverse section thereof.

In the drawings, *a* is a hollow box-body surrounded and surmounted by leaf-like projections *b*. 15

What I claim is—

The design for a box substantially as herein shown and described.

JOHN A. KIESELE.
